UNITED STATES PATENT OFFICE.

CHARLES F. STOCK, OF PEORIA, ILLINOIS.

BALL-TRAP.

SPECIFICATION forming part of Letters Patent No. 296,247, dated April 1, 1884.

Application filed December 22, 1883. (No model.)

To all whom it may concern:

Be it known that I, CHARLES F. STOCK, of Peoria, in the county of Peoria and State of Illinois, have invented a new and Improved 5 Device for Throwing Targets, of which the following is a full, clear, and exact description.

This invention relates to certain improvements in my new and improved device for throwing targets known as "clay pigeon and ball traps," shown and described in my application for Letters Patent which was allowed 10 September 28, 1883; and the present invention consists of an improved clamp for holding the target; in dispensing with a rear extension of 15 the arm and stud for suddenly stopping the swing of the arm, and in providing the rear weight with a lip or projection for holding the target in place upon the weight at the setting the trap, and of the construction, arrangement, and combination of parts, all as herein 20 after described and claimed.

Reference is to be had to the accompanying drawings, forming part of this specification, in which similar letters of reference indicate 25 corresponding parts in all the figures.

Figure 1 is a perspective view of my new and improved target-throwing device as it appears when set ready for throwing the target. Fig. 2 is a perspective view, showing the parts 30 in the position they assume just before the target leaves the trap; and Fig. 3, a perspective view of the outer end of the throwing-arm, and showing the improved clamp-plate.

A is the hollow post, to be driven into the 35 ground, provided with the pulley B.

C is the hollow head, placed in the upper end of the post A, and provided with the pulley D.

E is the main body of the device, hinged to 40 the head C upon the bolt F, on which the pulley D is journaled; and G is the throwing-pulley, which is pivoted to the main body E by bolt H, and which carries the throwing-arm I, and has the cord J attached to it. The weighted 45 end K of the main body E is not plain upon its upper surface, but is formed with the lip or projection L, for holding the target M in place, ready to be thrown, as illustrated in Fig. 1.

N is the clamp for holding the tongue O of 50 the target. This clamp is made of spring

metal, and is secured upon the upper surface of the throwing-arm I by the screw P, and is upwardly curved in the center and provided with the screw Q, for increasing or diminishing its clamping force. At its outer end, where 55 it grasps the tongue O, the clamp-plate is depressed, as shown at a, to form a swell or projection upon the under side of the clamp for holding the tongue O of the target; and to cause this swell or projection to effect a better 60 grasp upon the tongue O, I prefer to cut a portion of the depressed part, as shown at a', thus forming a tooth or spur upon the under side of the clamp N. The screw or bolt P reaches through the throwing-arm I, as 65 shown in dotted lines in Fig. 3, to form a stud, p, for the bent tension-spring R, (secured to the edges of the body E,) to engage with for holding the throwing-arm I in "set" position, as shown in Fig. 1. The forward portion 70 of the body E is formed with the flange b, which is cut away at c, where the cord J leaves the throwing-pulley G and passes down through head C and post A, over the pulleys D B, and this cut-away portion c is so formed as to form 75 the rounded shoulder d, which acts as a stop to the cord J in springing the trap, so as to suddenly stop the swinging motion of the throwing-arm I at the proper point, and thus cause it to project the target into the air with-out the aid of an extra or positive stop.

Constructed in the manner described, the device is very cheap and durable, and very effective for its purpose.

Having thus described my invention, what 85 I claim as new, and desire to secure by Letters Patent, is—

1. A throwing-arm for target-throwing traps, consisting of the arm and a curved spring-clamp on the outer end of said arm, 90 the said spring-clamp being secured at one end to the arm, and provided at or near its center with an adjusting-screw, and at its forward under side with a holding spur or tooth, substantially as set forth.

2. A throwing-arm for target-throwing traps, consisting of the arm and a curved spring-clamp on the outer end of said arm, 95 the said spring-clamp being secured at one end to the arm, and provided at or near its 100

curved central part with an adjusting-screw, and at its forward under side with a depression, a portion of the depression being cut away to form a holding-support, substantially as set forth.

5. The body portion for holding the target, pivoted to a suitable standard or base, and provided with a weight at its free end, on the upper face of which is secured a curved lip for 10 the target to rest against, in combination with a throwing-arm constructed to engage said target and remove it from said weighted portion and lip.

4. The combination of the body portion E, 15 hinged to a suitable standard, and provided near its outer end with a holding-spring, R, with the pivoted throwing-arm I, provided with the spring-clamp N near its outer upper end, and with a pin or lug on its under 20 side to engage the holding-spring R, and mechanism for releasing and throwing said throwing-arm, substantially as set forth.

5. The combination of the body portion E, hinged to a standard, A, and having its outer 25 end weighted at K, a lip, L, above said weight,

and a holding-spring, R, with the throwing-arm I, pivoted to the body E, and provided with the spring-clamp N, secured at one end to the arm by a bolt, P, which passes through the arm to engage the holding-spring R, and 30 said spring-clamp provided with an adjusting-screw near its center, and constructed to hold the target between its outer end and the throwing-arm, and mechanism for releasing and throwing said throwing-arm, substantially as 35 set forth.

6. The combination of the body portion E, hinged to a suitable standard, and provided with flange b, cut away at c to form a shoulder, d, with the throwing-arm I and pulley G, 40 pivoted to the flanged end of the body portion by bolt H, and a cord, J, secured to said pulley and passing through said cut-away portion of the flange, whereby a stop for the cord and throwing-arm is provided.
